ALTITUDE COMPENSATOR FOR FUEL PUMPS

Milton A. Trisler, Indianapolis, Ind., assignor to
General Motors Corporation, Detroit, Mich., a
corporation of Delaware

Application November 27, 1942, Serial No. 467,134

5 Claims. (Cl. 103—42)

1

An improvement in a pump serving to supply fuel to the engine of an airplane constitutes the subject matter of this invention.

The object of the invention is to provide for maintaining substantially constant absolute pressure, regardless of altitude, on the bypass valve or other pressure regulating mechanism of an airplane fuel pump. Other objects such as simplicity and efficiency will be understood from the description which follows.

An embodiment of the invention is shown by the accompanying drawing in which:

Figure 1 is a transverse section through a fuel pump combined with a bypass and having my improvement incorporated therein.

Figure 2 is a section on line 2—2 of Figure 1.

On the drawing, numeral 5 is used to identify a pump housing. It has an inlet 9 to receive fuel from a suitable source and an outlet 7 for connection to the carburetor. Between the inlet and outlet is a pump barrel 11 within which is an eccentric rotor 13 carrying the blades 15 and spacing roller 17 as in prior pumps. Above the housing 5 is a bypass valve support 19 and above part 19 is a dome-shaped cover 21, fastening means 23 securing the several parts together as shown.

Part 19 has an upper transverse but apertured wall 25, an intermediate transverse partition 27, and a circular inner tubular part 29 which latter is reduced in diameter at 31 to telescope within a similar sleeve part 33 of body 5. Between pump parts 19 and 21 is secured a flexible diaphragm 35. On the under side of the diaphragm is a flanged disc 37 integral with a tapered wall valve member 39 which engages a valve seat 41 on part 29. When the valve is seated the space above the valve and partition 27 is in communication with the discharge side of the pump by a passage 43 in the partition 27 and registering passages 45 and 47 in the pump members 19 and 5 respectively. The tubular part 29 is cut away to form an opening 49 by which the space within said part 29 is in communication through registering passages 51 and 53 in parts 19 and 5 with the low pressure (intake) side of the pump, the side leading from the fuel supply.

The part 21 of the assembly is open to the atmosphere at 55. A threaded member 57 in its upper face adjustably positions the upper abutment 59 of a spring 61. A sealed bellows or aneroid 63 of known construction is secured to abutment 59. Its lower end contacts the diaphragm 35. Spring 61 is within the bellows and exerts pressure on its lower face and on the dia-

2

phragm and valve, being operable to bias the valve upon its seat.

The operation of the device is as follows. It is important that the absolute fuel pressure for the carburetor should be substantially constant or should not fall off in proportion to the decrease of atmospheric pressure with increases in altitudes. To provide for all needs the pump capacity must be such that the pump outlet pressure 10 sure always tends to exceed the desired carburetor pressure. In consequence the bypass valve is at all times open, at least to some extent. The pressure at the pump outlet in excess of the constant pressure needed opens the valve, the underside of the diaphragm (which is greater in area than the bypass valve) being always in communication with the pump outlet by way of passages 47, 45 and 43. The fuel returns to the low pressure side of the pump by way of passage 49 and 53. The constant pressure desired is maintained by the proper adjustment at 57 of springs 61. At sea level the tendency of the sealed evacuated bellows to expand and exert pressure on the valve is partially balanced by the external 15 pressure on the bellows. When the device is used on an airplane, and the apparatus reaches higher elevations the reduced external air pressure permits the bellows spring 61 to exert increased pressure on the valve to maintain the pressure applied to the diaphragm and valve substantially constant. In the absence of the bellows, the pressure on the valve being the air pressure plus the spring pressure, would decrease as the plane reaches higher altitudes and with decreasing applied pressure the valve would open at 20 too low pump pressures and insufficient fuel would be supplied to the carburetor. It will be observed that the diaphragm 35 performs the important function of preventing the fuel under 25 the pressure conditions determined by the pump from reaching the space around the bellows with the result that the unbalance of air pressures is 30 free to operate as stated.

I claim:

45 1. In a fuel pump having a pressure regulator by-pass, a valve therefor, a spring and an altitude sensitive aneroid jointly operable on said valve, an air vented chamber containing said spring and aneroid and a flexible diaphragm connected to said valve and separating said aneroid chamber from said bypass the dimensions of the aneroid and the diaphragm being such that the air pressure within the chamber exerts a force 50 on the diaphragm tending to close the valve substantially equal to the force of said air pressure 55

acting on the aneroid in a direction to open the valve.

2. In a fuel pump, means forming a bypass between the high pressure and low pressure sides of said pump, a valve to close said bypass, a spring and an altitude sensitive aneroid operable jointly to bias said valve to closed position, an air vented chamber containing said aneroid, and a diaphragm sealing said chamber from said bypass the dimensions of the aneroid and the diaphragm being such that the air pressure within the chamber exerts a force on the diaphragm tending to close the valve substantially equal to the force of said air pressure acting on the aneroid in a direction to open the valve.

3. The invention defined by claim 2, said aneroid comprising a sealed and partially evacuated bellows having a fixed abutment at one end, the other end operably associated with said valve

to exert thereon variable pressures dependent upon external air pressure.

4. The invention defined by claim 2, together with adjustable means to determine the resilient force applied by said spring.

5. In combination, a fuel pump having a pressure regulating by-pass valve, means forming a chamber associated with said fuel pump, movable means secured to said valve and separating said pump from said chamber, said chamber being open to the surrounding air, a sealed aneroid and a spring within said chamber and jointly operable on said movable means, the dimensions of the aneroid and the movable means being such that the air pressure within the chamber exerts a force on the movable member tending to close the valve substantially equal to the force of said air acting on the aneroid in a direction to open the valve.
